TRAILER FRAME FOR A STUMP PULLING MACHINE

Gene A. Ulve, Lake Mills, Iowa, assignor to Tree-Mate
Corporation, Lake Mills, Iowa

Filed Feb. 9, 1973, Ser. No. 331,106

Term of patent 14 years

Int. Cl. D15—03

U.S. Cl. D40—1 E

FIG. 4

*FIG. 5**FIG. 6*FIG. 1 is a perspective view of a trailer frame for a stump pulling machine showing my new design,

FIG. 2 is a side elevational view thereof it being understood that the opposite side is substantially a mirror image of the side shown in FIG. 2,

FIG. 3 is a top plan view thereof,

FIG. 4 is a bottom plan view thereof,

FIG. 5 is a front elevational view thereof, and

FIG. 6 is a rear elevational view thereof.

I claim:

The ornamental design for a trailer frame for a stump pulling machine, as shown.
